UNITED STATES PATENT OFFICE.

FRANK J. GUTH, OF CHICAGO, ILLINOIS.

DEVICE FOR EXHIBITING COLLARS, SCARFS, &c.

SPECIFICATION forming part of Letters Patent No. 319,406, dated June 2, 1885.

Application filed February 6, 1884. (No model.)

To all whom it may concern:

Be it known that I, FRANK J. GUTH, a citizen of the United States, residing at Chicago, in the county of Cook and State of Illinois, have invented certain new and useful Improvements in Devices for Exhibiting Collars, Scarfs, &c., of which the following is a specification, to wit:

This invention relates to an improvement in devices for displaying collars and scarfs; and it consists in certain peculiarities of construction and arrangement of the same, substantially as will be hereinafter more fully set forth and claimed.

15 In order to enable others skilled in the art to which my invention appertains to make and use the same, I will now proceed to describe its construction and operation, referring to the accompanying drawings, in which—

20 Figure 1 is a front elevation of the device with a collar in position. Fig. 2 is a front view of the clamping device, and Fig. 3 is a central vertical section of the same.

A represents a metal plate or shield of any 25 desired shape or material, having a short horn or extension, a , at each of its upper corners, and its upper edge cut somewhat in the shape of a neckband of a shirt, and provided in its center with a projection, a' , formed 30 with an oblong button-hole, a^2 , as fully shown in Fig. 2. This shield is provided on its rear side with a spring-actuated clip, B, hinged in a projection or lug, b , and having a thumb-piece, b' , and two horns, b^2 , which bear upon 35 the rear side of the horns a of the shield and clamp the collar firmly in position. The whole is mounted in a spindle or rod, C, which is adjustable vertically in a hollow standard, C', having a suitable foot or base, as shown in 40 Fig. 1.

This device is intended for use in windows or show-cases, to display collars and scarfs in their natural position. The ends of the collar are brought together and secured by a button, the shank of which also passes through the hole a^2 of the shield, and the sides of the collar are clamped between the fingers or horns a^2 , and held in the same position assumed when in use. The scarf is then adjusted to place, and the shield being bent to 45 about the shape assumed by a shirt-bosom, it is held in proper position.

The scarf or collar may be exhibited either singly or together, and the standard being an extension one, many different articles may be 55 shown to advantage in rows, one behind the other, each successive one being lifted above the other to better exhibit it.

It is evident that shirts may also be displayed by this device and given any desired 60 angle by raising or lowering the standard, one end of the shirt resting on the show-case, and the other grasped and held up by the clamp.

It is obvious that the number of bearing or clamping points may be varied at pleasure 65 and other modifications may be made without departing from the spirit of the invention, which is to hold the article to be displayed in its natural position and show it to the best advantage, and this may be done equally well 70 by plates clamping all the way from corner to corner, instead of being cut away, as shown, to form clamping-fingers, and this I regard as the equivalent of my construction, the horns or fingers being only bearing-points for clamp- 75 ing purposes.

Having thus fully described my invention, what I claim as new, and desire to secure by Letters Patent, is—

1. In a device for exhibiting collars, a shield 80 or plate having two bearing fingers or horns, in combination with a spring-clip arranged upon its rear side, also provided with clamping-points, substantially as and for the purpose set forth.

2. In a device for exhibiting collars, a plate 85 or frame formed or provided with clamping-fingers at its upper corners and a button-hole in its center, in combination with a spring-clip hinged upon it, and a supporting standard or base, substantially as and for the purpose set forth.

3. The plate A, formed with horns a , projection a' , and hole a^2 , in combination with the spring-clip B, having bearing-horns b^2 , and the 95 rod C, hollow standard C', and a base or foot, substantially as and for the purpose set forth.

In testimony whereof I affix my signature in presence of two witnesses.

FRANK J. GUTH.
